US00D618860S

(12) **United States Design Patent**
Friedland et al.

(10) **Patent No.:** **US D618,860 S**
(45) **Date of Patent:** **** Jun. 29, 2010**

(54) **MULTI-PIECE FEEDING BOWL**

(75) Inventors: **Jason Michael Friedland**, Franklin, TN (US); **Gary N. Chisholm**, Rancho Palace Verdes, CA (US); **Diana L. Ortiz**, Tarrytown, NY (US); **Michael J. Wilson**, Rossmoor, CA (US); **Kevin Rabinovitch**, Redondo Beach, CA (US); **Hanif Matthew Wadalawala**, Manhattan Beach, CA (US); **Ruth Moecks**, Franklin, TN (US); **Jane Elkins**, Redondo Beach, CA (US)

(73) Assignee: **Mars, Incorporated**, McLean, VA (US)

(**) Term: **14 Years**

(21) Appl. No.: **29/328,519**

(22) Filed: **Nov. 25, 2008**

(51) **LOC (9) Cl.** **30-03**

(52) **U.S. Cl.** **D30/129**

(58) **Field of Classification Search** ..... D30/121, D30/122, 129-133, 101; 119/61.5, 51.01, 119/61.56, 51.03, 59, 62, 63, 51.5, 57.8, 119/74, 61.54, 61.55; 312/204; 248/151, 248/188; 108/156, 153.1-157; 220/23.87, 220/630, 737, 743, 9.4, 495.01, 574, 212, 220/255, 23.83, 606, 657, 257.2, 359.2, 359.3, 220/253, 254.2, 507, 326, 825, 835; 206/538, 206/533, 534; D7/586, 543, 550.1, 587, D7/505, 584, 545, 500, 553.1-553.8, 546, D7/555, 556, 504, 565, 562, 602, 676, 544, D7/548, 675, 554.2, 551.1, 672, 677; D9/429, D9/425, 603, 443, 414-424, 428, 430-434, D9/450, 523-525, 715, 503; 43/109; D22/122; 99/430, DIG. 15; D27/106, 113, 114; 229/406, 229/123.1, 125.05, 125.35, 404, 123.2, 123.3, 229/125.13, 125.14; 426/104; D3/203.1-203.4, D3/206, 294; D19/51, 84, 85; D11/149-152; D24/121, 123

CLAIM

The ornamental design for a multi-piece feeding bowl, as shown and described.

DESCRIPTION

FIG. 1 is a top perspective view of a multi-piece feeding bowl showing our new design;

FIG. 2 is a bottom perspective view of the design shown in FIG. 1;

FIG. 3 is a front view of the design shown in FIG. 1;

FIG. 4 is a rear view of the design shown in FIG. 1;

FIG. 5 is a left side view of the design shown in FIG. 1;

FIG. 6 is a right side view of the design shown in FIG. 1;

FIG. 7 is a top view of the design shown in FIG. 1; and,

FIG. 8 is a bottom view of the design shown in FIG. 1.
